UNITED STATES PATENT OFFICE.

JOHN HENRY, OF GRAND FORKS, NORTH DAKOTA.

GRAIN-DOOR FOR CARS.

1,000,807.

Specification of Letters Patent. Patented Aug. 15, 1911.

Application filed August 24, 1910. Serial No. 578,648.

To all whom it may concern:

Be it known that I, JOHN HENRY, citizen of the United States, residing at Grand Forks, in the county of Grand Forks and 5 State of North Dakota, have invented new and useful Improvements in Grain-Doors for Cars, of which the following is a specification.

My present invention pertains to grain 10 doors for cars; and it consists in the simple, practical and advantageous grain door hereinafter described and claimed.

In the drawings, accompanying and forming part of this specification: Figure 1 is an 15 elevation taken from a point within a car and showing my improvement in position to close the lower portion of the door opening. Fig. 2 is a horizontal section taken in the plane indicated by line 2—2 of Fig. 1, looking 20 downward. Fig. 3 is a detail section taken in the plane indicated by line 3—3 of Fig. 1, and showing the upright bar of the fastening means and the portions of the doors adjacent thereto. Fig. 4 is a detail 25 vertical section taken in the plane indicated by the line 4—4 of Fig. 1, looking toward the right. Fig. 5 is a view similar to Fig. 1 but showing all of the parts positioned to afford a clear door opening. Fig. 6 is a detail 30 vertical section, taken in the plane indicated by line 6—6 of Fig. 5, looking toward the right, and showing the swinging bar by full lines in its lower position, and by dotted lines in its upper position. Fig. 7 is a detail 35 perspective of the upper end of the upright bar comprised in the fastening means. Fig. 8 is a horizontal section taken in the same plane as Fig. 2 and illustrating a modification hereinafter specifically referred to.

40 Similar letters of reference designate corresponding parts in Figs. 1 to 7.

The bar A above the door opening B is provided in its inner side with a recess a, and the upper portions of the door posts C 45 are rabbeted, as indicated by b.

Pivoted to the posts C at points c in the rabbets b are the arms d of the horizontal, vertically-swinging bar D comprised in the means for fastening—i. e., supporting and 50 preventing outward movement of the doors, hereinafter described. On its forward side the bar D is provided with a projection e, and to the rear side of said bar is loosely connected a pendent handle f. Thus when 55 the bar D is swung up into the position shown in Figs. 5 and 6 to clear the door

opening, the projection e will be accommodated in the recess a, while the handle f will depend so that when desired the bar can be conveniently pulled down into its working 60 position shown in Figs. 1 and 2.

For the purpose of detachably securing the bar D in its upper and idle position, I prefer to employ the latch E. This latch is pivoted at g, and its inner and comparatively heavy arm is provided with a depending portion h which rests between the inner side wall of the car and a strap i attached thereto, and is adapted to retain the bar D against the bar A. The outer arm of said 70 latch E is provided with a tail portion j, designed for the engagement of a hook-bearing rod or other device employed to raise the inner arm of the latch with a view to releasing the bar D precedent to pulling the 75 same down through the medium of the before mentioned pendent handle f.

In addition to the bar D, the door fastening and supporting means comprises an upright bar F, upright strips G fixed to the 80 inner sides of the door posts C and forming therewith rabbets k, lower keepers l and upper keepers m, carried by and projecting beyond the inner edges of the strips G, and keepers p carried by the bar F and projecting beyond the sides of the inner portion r thereof and located in a horizontal plane slightly above that of the keepers l. The bar F comprises the mentioned inner portion r and a comparatively wide outer portion s 90 against which the adjacent portions of the doors H are adapted to bear outward, as clearly shown in Figs. 2 and 3. The lower end of the bar F is removably seated in a recess in the door sill t and between said sill 95 and a fixed strip u, and, as best shown in Fig. 7, the inner portion r of the said bar is extended above the outer portion s thereof and is notched, as indicated by v, to receive the projection e on bar D. When the bar D 100 is in working position it rests between the said notched end of the bar portion r and an upwardly extending flange w on the outer bar portion s, and consequently the bar D serves to hold the bar F in its upright position and in the recess in sill t and against outward movement. When, however, it is desired to clear the door opening B, as when 105 large pieces of merchandise are to be moved therethrough, the bar D is swung inwardly 110 and upwardly, whereupon it will be disengaged and separated from the bar F, and

then said bar F may be lifted out of its socket between sill *t* and strip *u*, and stored away for future use.

To position the bar F and bar D for use, 5 the manipulation described is reversed—*i.e.*, the bar F is placed in the socket between sill *t* and strip *u*, and then, while the bar F is inclined slightly inward, the bar D is positioned between the notched end of the bar 10 portion *r* and the flange *w*, after which the adjacent portions of the bars F and D are swung outward until they rest in a vertical position, whereupon the bar D will be seated between the notched portion and the flange 15 *w*, and with its projection *e* in the notch *v*, in which position the bar D will serve the purpose heretofore ascribed to it.

The doors H are preferably, though not necessarily, flat steel plates, and while I 20 show the said doors as connected through chains I with the side wall of the car body, I do not confine myself to the use of chains or any other connecting means, since without affecting my invention the doors H may 25 be entirely unconnected with the car body.

To put the doors H in the position in which the same are used, which position is shown by full lines in Fig. 1, it is simply necessary to place the doors, while in a position above the keepers *p*, against the rabbets *k* and the inner side of the outer portion *s* of the bar F. The doors are then slid downward until they rest on the floor of the car body, and then, as will be manifest, the 30 doors will be confined between the outer walls of the rabbets *k* and the inner side of the portion *s*, on the one hand, and the keepers *l*, *m* and *p*, on the other hand. When thus placed the doors will bear outward 35 against the outer walls of the rabbets *k*, the portion *s* of bar F, and the bar D, and consequently outward movement of any portion of either door is effectually prevented. It 40 will also be manifest that the doors are securely fastened in position and are braced or reinforced and supported by the door posts, the bar F and the bar D.

When it is desired to discharge grain or other substance carried in bulk from the car body through the portion of the door opening controlled by either door, it is simply necessary to raise either door to a point 45 above the keepers *p*, and then swing or otherwise move the said door to the position shown in Fig. 5.

In Fig. 8, I illustrate a modified construction in which a sheet-metal upright bar F^s, of channel-form in horizontal section, is employed in lieu of the upright bar F, heretofore referred to, and the bar D^s (which may 60 be made of metal, wood or other suitable material) is adapted to afford a bearing for flanges s^s on said bar F^s, while the said flanges are designed, in turn, to afford bearings for the doors H^s which are confined

thereagainst by keepers p^s on the lower portion of the bar F^s, in the manner before described. With the exceptions noted, the modified construction is similar to that shown in Figs. 1 to 7; it being noted, however, that in said modified construction it is unnecessary to provide a recess such as *a* of Figs. 1 and 6, in the top bar of the door frame. 70

While I have shown and described two 75 forms of my present invention, it is to be understood that I am not limited to the details or the form or relative arrangement of parts disclosed, but that modifications may be made therein without departing from the 80 spirit thereof.

When desired a pull cable (not shown) may be attached to the tail-portion *j* of the latch E so that said latch can be conveniently moved; the tail-portion *j* being preferably apertured for said purpose as shown in Fig. 6. 85

In both of the disclosed embodiments of 90 my invention, the swinging bar is preferably a steel pipe of rectangular form in cross-section, this in order to secure both strength and lightness. 95

Having described my invention, what I claim and desire to secure by Letters-Patent, is:

1. In a grain door for cars, the combination of a car body having a door opening and door posts equipped with rabbets, and also having a socket located intermediate the posts; an upright bar movable vertically into and out of the socket and having a comparatively wide outer portion, an upwardly extending and notched inner portion and an upwardly extending outer portion spaced from said inner portion; a vertically swinging bar held against outward movement by the posts and constructed to seat between said upwardly extending portions of the upright bar and having a projection to seat in the notch of the inner portion and also having arms pivoted to the posts, vertically movable doors that bear outward against the posts, the outer wide portion of the upright bar and the vertically swinging bar and are arranged in the rabbets of the posts, and keepers in the posts and other keepers on the upright bar and arranged in a different horizontal plane from those on the posts, for holding the doors against the posts and the wide portion of the upright bar. 110 115 120

2. In a grain door for cars, the combination of a car body having a door opening and door posts and also having means intermediate the posts for holding one end of an upright bar; the said upright bar movable vertically into and out of engagement with said means; a vertically swinging bar held against outward movement by the posts and having arms pivoted to the posts; said upright bar and vertically swinging bar be- 125 130

- ing constructed to interlock and enable the latter to hold the former; vertically movable doors that bear outward against the posts, the upright bar and the vertically swinging bar; and keepers on the posts and other keepers on the upright bar and arranged in a different horizontal plane from those on the posts, for holding the doors against the posts and the upright bar.
- 5 3. In a grain door for cars, the combination of a car body having a door opening and door posts and also having means intermediate the posts for holding one end of an upright bar; the said upright bar movable vertically into and out of engagement with said means; a crosswise bar held against outward movement by the posts; said upright bar and crosswise bar being constructed to interlock and enable the latter to hold the former;
- 10 20 25 4. In a grain door for cars, the combination of a car body having a door opening and door posts; vertically movable doors that bear outward against the posts, the upright bar and the crosswise bar; and keepers on the posts and other keepers on the upright bar and arranged in a different horizontal plane from those on the posts, for holding the doors against the posts and the upright bar.
- 30 35 5. In a grain door for cars, the combination of a car body having a door opening and door posts and also having means intermediate the posts for holding one end of an upright bar; and means for preventing outward movement of a door, comprising the said upright bar movable vertically into and out of engagement with said means, and a vertically swinging bar held against outward movement by the posts and having arms pivoted to the posts; said upright bar and vertically swinging bar being constructed to interlock and enable the latter to hold the former.
6. In a grain door for cars, the combination of a car body having a door opening and door posts and also having means intermediate the posts for holding one end of an upright bar; and means for preventing outward movement of a door, comprising the said upright bar movable vertically into and out of engagement with said means, and a crosswise bar held against outward movement by the posts; said upright bar and crosswise bar being constructed to interlock and enable the latter to hold the former.

In testimony whereof I have hereunto set my hand in presence of two subscribing witnesses.

JOHN HENRY.
